UNITED STATES PATENT OFFICE.

STEWART WARING, OF EVANSTON, ILLINOIS, ASSIGNOR TO SEARS, ROEBUCK AND COMPANY, OF CHICAGO, ILLINOIS, A CORPORATION OF NEW YORK.

PAPER-WINDING MECHANISM.

1,081,933.

Specification of Letters Patent. Patented Dec. 16, 1913.

Application filed June 19, 1912. Serial No. 704,501.

To all whom it may concern:

Be it known that I, STEWART WARING, a citizen of the United States, residing at Evanston, in the county of Cook and State 5 of Illinois, have invented certain new and useful Improvements in Paper-Winding Mechanism, of which the following is a specification.

This invention relates to mechanism for 10 winding strips of paper or similar material into rolls.

One of the objects of the invention is to provide mechanism so that the strips may be wound into suitable rolls without the use 15 of a core or central mandrel upon which the strips are wound.

The machine to which the invention more particularly relates is of that type illustrated and described in Letters Patent No. 20 999,852, granted to me August 1, 1911. In that machine mechanism is provided for winding strips of paper into rolls without the use of the central core or mandrel. And the mechanism herein illustrated and described is adapted to more effectively carry 25 on the rolling process, particularly when the end of the strip is caused to curl upon itself and form the central turn of the roll. It has been found that, with the mechanism 30 described in said patent, at times the end of the strip would become bent and crinkled somewhat before it would begin to roll properly. And to avoid this is one of the objects of this invention.

35 In the accompanying drawings, Figure 1 is a vertical transverse section of a winding mechanism which embodies features of my invention. Fig. 2 is a perspective view 40 of a member used in the mechanism to properly guide the end of the strip in order to form the first turn of the roll and to assist in forming subsequent turns. Fig. 3 is a detail view of a portion of two of the roll-forming rotary members.

45 The machine described in the patent referred to has a set of rollers encircling the space in which the strip roll is formed. And as the strip of paper or other material is fed by other rollers into this roll-forming space 50 the end of the strip is guided by each of the

rollers in succession as the strip end comes in contact with the roller so as to form a suitable central turn upon which the remainder of the roll is wound. The mechanism herein shown is of the same general 55 structure; but herein one of the rollers shown in said patent is replaced by a stationary guide member along the surfaces of which the end of the strip is pushed; and these surfaces, in conjunction with the peripheries 60 of the rollers, cause the end of the strip to curl upon itself and make a suitable turn for the center of the roll. As a result of this arrangement there is no bending or crinkling of the end of the strip, and the 65 central turn of the roll is as suitably wound as any other turn.

The roller mechanism comprises four rollers 1, 2, 3 and 4. These rollers are composed of the central portion or shafts 70 5, 6, 7 and 8, each having a series of annular ribs or flanges 9 thereon. The shafts of the rollers 1 and 2 are journaled in bearings fixed to the frame 10 of the machine; and the shafts of the rollers 3 and 4 are journaled in bearings in upright pieces 11 which are pivoted to the framework at their lower ends. These uprights are yieldingly held in place by means of the link 11^a, the arm 11^b pivoted to said link and to the 75 framework, the link 11^c, and the spring 11^d attached to the framework, as is more fully shown and described in said patent. And they thus hold yieldingly the rollers 80 3 and 4 normally in contact with the rollers 1 and 2, allowing them, however, to be pressed away from rollers 1 and 2 as the roll of paper enlarges, so as to keep the roll snugly and properly wound. Means 85 are also provided whereby when the roll is completed the uprights 11 are forced outwardly so as to allow the roll to drop downwardly between the lower separated rollers, as is fully described in said patent.

The paper strip 12 is fed, by means of 90 suitable primary feed rollers, to the secondary feed rollers 13 and 14. The rollers 13 and 14 are suitably mounted in bearings fixed in the framework 10 of the machine; and the roller 13 is yieldingly pressed 100

against the roller 14 by means of a spring 15 at each end of the roller, compressed between a collar 16, fixed to an adjustable screw 17, and a slidable block 18 which 5 presses against the end of the shaft of the roller 13. The screw 17 is threaded into the fixed block 19. The rollers 13 and 14 also have annular ribs or flanges 20 on the shaft portions, and between these flanges 10 are a plurality of guide strips 21 and 22 attached to the framework by the screws 23. The free ends of the strips 21 pass between the flanges of the roller 1; and the outer ends of the strips 22 support the 15 guide member 24, which is positioned between the rollers 1 and 2. Adjacent the point of junction of the strips 22 and the guide member 24 the edges 24a of the member are upturned so as to prevent the 20 ends of the paper strips striking against the edges.

The paper strip which is to be formed into a roll is forced along these guides 21 and 22 into the roll-forming space, and as it passes 25 into this space is bent downwardly by the guide 24, as indicated, and passes over until it comes in contact with roller 3. The flanges of each of these rollers run between the flanges of the adjacent roller so that 30 the end of the strip cannot pass between the two rollers, except in case of the rollers 1 and 2. Also each of the flanges on the rollers 2, 3 and 4 has on its periphery a plurality of notches 25; and as the end of the 35 paper strip comes in contact with these flanges the end is forced, by means of these notches, in the direction of rotation of the roller.

The rollers may be rotated by any suitable 40 means. The roller 2 may be rotated by means of the gear wheel 26 fixed to the shaft of the roller, the idle gear wheel 27, and the gear wheel 28 fixed to the shaft of the roller 14; and the gear wheel 28 may be rotated in any suitable manner. In a similar 45 way roller 1 may be rotated. Roller 4 may be rotated by means of a belt 29 passing over a grooved pulley 30 fixed to the end of shaft 8 and operated in any suitable manner; 50 and roller 3 may be operated in a similar manner.

The roll-forming rollers are all rotated in the same direction. In this instance the 55 direction of rotation, as indicated by the arrows, is counterclockwise (Fig. 1). As the end of the strip comes in contact in the manner hereinbefore described with the roller 3, the end is carried upward in contact with the roller 4, thence backward in 60 contact with the roller 2, thence in contact with the curved upwardly extending projections 31 on the guide member 24, and thence downward along the surface of these pro-

jections until it comes in contact with the strip itself and is thus forced continuously around, forming perfect turns. As the process continues the rollers 3 and 4 are forced, by the paper roll 32, outwardly so as to enlarge as needed the space in which the roll is being formed. When the roll is of the required size, suitable mechanism is set in operation in a manner fully described in said patent, and the knife 33 is forced downwardly severing the strip; the rolling process is continued until the projecting end strip is wound around the roll; the mechanism then forces outwardly rollers 3 and 4 and the completed roll falls to a suitable receptacle. The severed end of the strip is then forced inwardly between the two secondary feed rollers and the process is continued.

By suitably positioning the roll-forming rollers, and the guide member 24, and by suitably shaping the surface of the guide member 24, the roll may thus be formed without the use of a central core or mandrel, and without bending or crinkling any of the turns of the roll.

By arranging to rotate the roll-forming rollers at a somewhat greater rate than that of the primary feed rollers, shown in said patent, any slack that may accumulate between the time of finishing one roll and beginning the next will be taken care of.

I claim as my invention:

1. In a paper-winding machine, a plurality of roll-forming members, a stationary guide coöperating with said members to inclose a roll-forming space, and means for rotating said members, said guide having two guiding surfaces, said surfaces being positioned adjacent the paper entrance to said space, one of said surfaces being adapted to impart the initial curve to the paper to be wound, the other surface being adapted to complete the central convolution of the roll to be formed.

2. In a paper-winding machine, a plurality of roll-forming members, means for rotating said members, a stationary guide coöperating with said members to inclose a roll-forming space, said guide having two guiding surfaces, said surfaces being substantially at right-angles to each other, one of said surfaces adapted to start the central turn of the roll to be formed and the other being adapted to complete the central turn.

3. In a paper-winding machine, a plurality of roll-forming members, means for rotating said members, and a stationary guide coöperating with said members, said guide having a guiding surface thereof adapted to engage the central end of the paper to be rolled and to complete the central turn of said roll.

4. In a paper-winding machine, a stationary guide and a plurality of rollers annularly positioned so as to inclose a roll-forming space, a plurality of annular flanges on the periphery of each of said rollers, said flanges being positioned between the flanges on adjacent rollers, said guide having projections positioned between the flanges on one of said rollers, said projections being adapted to impart the final turn to the central convolution of the roll to be formed.

In witness whereof I hereunto affix my signature in the presence of two witnesses.

STEWART WARING.
